(21) Appl. No.: **29/303,835**

The ornamental design for a tray and handle assembly for rotary actuation latch, as shown and described.

(22) Filed: **Feb. 19, 2008**

DESCRIPTION

(63) Continuation-in-part of application No. 11/682,463, filed on Mar. 6, 2007.

FIG. 1. is a front perspective view of a tray and handle assembly for rotary actuation latch according to an embodiment of the invention with the handle raised to an actuating position; FIG. 2 is a front view of the tray and handle assembly for rotary actuation latch of FIG. 1;

(51) **LOC (9) Cl.** **15-09**

FIG. 3 is a right side view of the tray and handle assembly for rotary actuation latch of FIG. 1;

(52) **U.S. Cl.** **D15/142**

FIG. 4 is a left side view of the tray and handle assembly for rotary actuation latch of FIG. 1;
